UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCH MECHANISM WITH DOOR-INTERLOCK.

1,342,549.

Specification of Letters Patent.

Patented June 8, 1920.

Original application filed August 2, 1917, Serial No. 184,011. Divided and this application filed February 11, 1919. Serial No. 276,347.

To all whom it may concern:

Be it known that I, HUBERT F. KRANTZ, residing at Brooklyn, in the county of Kings and State of New York, have invented certain new and useful improvements in a Switch Mechanism with Door-Interlock, of which the following is a specification.

This is a division of my pending application Serial No. 184,011, multiple unit safety switch board, filed August 2, 1917.

The object of this invention is to provide improved safety mechanism for preventing accidents to the operators of switch boards.

A further object is to provide improved means whereby a switch protecting member is held against being displaced while any of the parts, which might be accessible when said guard member is displaced, are live.

A further and more detailed object is to provide a switch container having a door giving entrance thereto, and to provide an improved switch mechanism within the container having switch operating means which may extend to the front face of the board, and the switch mechanism being adapted to prevent opening of the door while the switch is "on" and to prevent "on" movement of the switch while the door is open.

A further object is to provide a mechanism as above referred to, which, while it is herein shown and described as being associated with a switch board structure, may obviously be employed in connection with individual switch containers of other types, such for instance as disclosed in my Patent 1,248,431, of November 27, 1917.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a vertical transverse sectional

view illustrating a switch mechanism and associated parts constructed in accordance with this invention, the section being taken substantially upon the plane of line I—I of Fig. 2.

Fig. 2 is a rear elevational view of a part of a switch board, parts being broken away to better disclose the construction.

Fig. 3 is a horizontal section view taken substantially upon the plane of line III of Fig. 1.

Fig. 4 is an enlarged fragmentary sectional view taken substantially upon the plane of line IV of Fig. 1.

Fig. 5 is a similar sectional view showing the parts of Fig. 4 with the switch mechanism in the "off" position and the door open.

Fig. 6 is a diagrammatic view of a portion of the structure of Fig. 1, showing the position of the parts when the switch is in the "on" position, with the door yet closed.

Fig. 7 is a diagrammatic view showing the parts of Fig. 5 as they appear with the door open.

Fig. 8 is a detail sectional view taken substantially upon the plane of line VIII of Fig. 5, and

Fig. 9 is a detail perspective view of the connecting link which extends from the switch mechanism to the door.

Referring to the drawings for describing in detail the exemplary structure illustrated therein, the reference character L indicates the main, or base plate of the switch board.

Two sets of bus bars, as 1 and 2, are fixed to the rear surface of the base plate, all in substantially parallel relation and extending vertically of the plate.

At the opposite vertical edges of the plate are branch line wire channels 3 made up of wall members 4 and 5.

An intermediate partition 6 is arranged between the branch line wire channels 3 and between the sets of bus bars.

The space between the partition wall and either of the walls 4 is divided vertically by any number of horizontal partitions 7 so as to divide said space into a desired number of superposed pockets, or stalls. Each stall

is closed at the rear by a separate guard member, or door G and each stall is adapted to removably contain an independently formed and independently operable switch unit, as clearly set forth in the application of which this is a division.

The switch units each comprise a base board 8, preferably of insulating material such as slate, and when the unit is inserted 10 into the stall this base board stands substantially parallel with the rear surface of the base plate L but spaced away therefrom so as to constitute a barrier within the stall for the bus bars so that said bus bars may not be carelessly touched by an operator when the door is open. Suitable fuse clips 9 and 10 are arranged upon the rear surface of the barrier for retaining fuses 11.

Contact members 12 are provided at the 20 forward face of the base board or barrier 8 for coacting with the switch blades 13. The contact members 12 are arranged opposite to the adjacent main line bus bars as 1, and there is, of course, one switch blade for each 25 bus bar and one contact 12 for each switch blade. The contacts 12 are electrically connected with the fuse clips 10 preferably by means of bolts which extend through the barrier to hold the fuse clips and contact 30 members in position. The fuse clips 9 are carried by suitable plates to which the branch line terminals 14 may be connected, as clearly shown in Fig. 1.

The switch blades 13 are supported in an 35 elongated carrier 15. This carrier is pivoted to rock about its longitudinal axis, suitable extensions 16 being provided at its opposite ends to engage within bearings formed in supporting plates 17. The blades 40 are spaced apart along the length of the carrier and project laterally therefrom. They are insulated from each other as by means of the insulating strips 18. The blades are double-ended so in "on" position 45 their opposite ends engage the bus bars 1 and the contact members 12 respectively.

The supporting plates 17 are carried by the barrier by means of bracket plates 19. These bracket plates are arranged one at 50 each edge of the barrier and at right angles to the plane of the barrier. They are fixed to the barrier preferably by means of bolts, or rivets 20. The supporting plates 17 are riveted, or otherwise secured, to the inner 55 surface of the plates 19 and extend forwardly beyond the barrier, as clearly indicated.

Of course, it will be understood that any 60 other suitable means may be employed for connecting the supporting plates 17 with the barrier. The principal requirement in this connection is simply that the supporting plates and all of the parts carried thereby shall be in turn carried by the barrier so

as to be bodily insertible into the stall and 65 bodily removable from the stall with the barrier.

The barrier may be considered as a frame, or carrier, for the switch mechanism, contacts, and fuse clips, by means of which all 70 of said parts may be readily arranged in proper cooperative position with the bus bars.

When moving a switch unit into position within a stall it is simply necessary to rest 75 the barrier upon the horizontal partition 7 forming the bottom wall of the stall and then to move it inwardly until the upper and lower portions of its forward face engage against suitably arranged cross members 80 21. Attaching screws may then be inserted through mating apertures to fix the barrier to said cross members.

The position of the cross members is such, with respect to the rear surface of the base 85 plate L, as to properly and positively determine the position of the forward face of the barrier with respect to the bus bars 1 when the barrier is moved home against the cross members. The switch blades and contacts 90 12 are likewise properly positioned by the cross members at the same time.

The walls 4 of the wire channels 3 are formed with suitable openings 22 through which the branch line wires may extend 95 into communication with the terminals 14.

The construction of the switch mechanism, and its manner of control, includes a bell-crank which is pivotally mounted, as at 23, upon the outer supporting plate 17. This 100 bell-crank is preferably made up of two plates, as 24 and 25, spaced apart. At the end of one of the arms a link 26 is pivotally mounted between the plates 24 and 25 and extends into pivotal connection with the 105 switch blade carrier 15, the point of connection with said carrier being at one side of the pivotal axis of the carrier; as at 27. The bell-crank and the link 26 constitute a toggle by means of which to swing the 110 switch blades to "on" and "off" positions.

An operating rod 28 extends between the plates 24 and 25 and has slot connection with a cross pin 29 at the remaining end of the bell-crank. This operating rod 115 extends forwardly through an opening 30 in the base plate L and is connected to be operated by a handle 31 at the front of the base plate.

Thus, when the handle 31 is moved into 120 a vertical, or "on" position, the rod 28 swings the bell-crank and straightens the toggle so as to hold the switch blade "on" as shown in Fig. 1. On the other hand, when the handle is thrown down into "off" 125 position, the rod 28 is moved backwardly so that the rear end 32 of its slot engages the cross pin 29 and swings the bell-crank to

break the toggle and to permit the switch blade to snap into "off" position, as shown in Fig. 6.

5 A coil spring 33 is arranged at the opposite end of the carrier, in engagement between the carrier and the adjacent supporting blade 17 so as to exert a constant tendency to move the carrier into the "off" position, the slot in the rod 28 providing for 10 an unobstructed movement of the toggle into "off" position once the toggle is broken.

In order to prevent the guard member, or 15 door G, from being opened while the switch is "on", said door is preferably mounted upon hinges 34 at the rear edge of the wall 4 and a link 35 is pivotally mounted thereto, as by a pin 36, carried by a stud 37 fixed to the door. The stud supports the pin 36 at a point removed from the axis of the hinge. 20 The link 35 is shaped substantially as shown in Fig. 9 and its inner end carries a lug 38 which slides backwardly and forwardly along a slot 39 formed in the adjacent plate 17 whenever the door is opened or closed. A 25 transverse head 40 is formed at the outer end of the lug to prevent accidental detachment of the lug from the slot.

The plate 25 of the bell-crank above described, is enlarged and is provided with 30 an arcuate slot 41 through which the lug 38 extends, the plate 25 being interposed between the plate 17 and the link 35. One end of the slot 41 terminates in a radial extension slot 42. When the bell-crank is 35 in the "on" position, the lug 38 stands at one end of the arcuate slot and the engagement of the walls of this slot with the lug prevents the lug from moving outwardly to permit opening of the door, and thus, 40 of course, prevents the door from being opened. So long as the door is closed the bell crank may be swung freely, the lug being accommodated by the arcuate slot.

When the bell-crank is in the "off" position, the extension slot 42 will stand in 45 parallelism with the slot 39, and the door may then be opened at will, the lug 38 traveling along the length of the two slots, as clearly shown in Figs. 6 to 8.

50 After the lug 38 is moved into the slot 42, said lug serves as a positive stop against any return rotation of the plate 25, thus locking the switch mechanism in the "off" position whenever the door is opened.

55 It will be apparent that, while the wall members 4 and 6, the base plate L and the door G, and the horizontal partitions 7, as herein shown and described, constitute elements of a structure which includes a plurality of stalls for receiving independent switch mechanisms, nevertheless in so far as the invention herein disclosed is concerned, said elements simply constitute an enclosure 60 for the switch mechanism as suggested by

the structure shown in the patent above referred to. 65

Each switch unit, as herein described, includes a barrier spaced back of the board and providing a safe fuse compartment and a guarded switch compartment, and the 70 switch mechanism included in the unit is of such construction and is so associated with the door that the door may not be opened except when the fuse terminals are "dead" and so that the switch mechanism may not 75 be moved to the "on" position to render the fuse terminals "live", when the door is closed.

When it is desired to remove one of the 80 switch units, it is simply required to throw the switch "off", open the door, remove the barrier retaining screws, disconnect the link 35 and rod 28 from the door and switch handle, and then lift the switch unit away where it may be conveniently operated upon 85 to any extent and then as readily returned.

When the link 35 has been disconnected from the door and has swung downwardly into a vertical position, its head 40 will register with the slot 39 and may be readily 90 disconnected therefrom if desired.

As many changes could be made in this construction without departing from the scope of the invention as defined in the following claims, it is intended that all matter contained in the above description or shown in the accompanying drawings, shall be interpreted as illustrative only and not in a limiting sense. 95

Having thus described my invention, what 100 I claim as new and desire to secure by Letters Patent is:

1. A switch board comprising a supporting member, a movable switch blade supported thereby, means forming an enclosure 105 for the switch blade including a guard door, operating means for operating the switch blade including a slotted plate, a second slotted plate, and means movable in the slots of said two plates extending into connection with the door adapted to prevent movement of the switch into "on" position except when the door is closed.

2. A switch board comprising a face plate, a movable switch blade, a supporting 115 member for the switch blade, means forming an enclosure for the switch blade including a guard door, a link connected with the door extending toward the switch mechanism and having a lug at its end slidably 120 engaging within a slot formed in the supporting member to move back and forth along said slot as the door is opened and closed, operating means for operating the switch blade including a plate pivotally 125 mounted upon said supporting member, said plate having a slot formed therein extending radially from its pivot through which

1. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, and means connected to move with the door having a part extending into the slot of said plate adapted to prevent movement of the switch blade into "on" position except when the door is closed.
2. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, and means connected to move with the door having a part extending into the slot of said plate adapted to prevent movement of the switch blade into "on" position except when the door is closed, and said plate having an arcuate slot formed at one end of its radial slot adapted to receive said lug upon movement of the switch into "on" position when the door is closed and to lock the lug against movement along the slot in the supporting member when the switch is "on".
3. A switch mechanism comprising a casting having an opening thereinto, a door for said opening, a switch blade, operating means for operating the switch blade, said operating means including a pivotally mounted plate having a slot formed therein, and means connected to move with the door having a part extending into said slot co-operative to prevent movement of the switch blade into "on" position except when the door is closed.
4. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, and means connected to move with the door having a part extending into the slot of said plate adapted to prevent movement of the switch blade into "on" position except when the door is closed.
5. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, a stationary member fixed adjacent said plate having a slot therein, and means connected to move with the door having a part extending into the slot of said plate adapted to prevent movement of the switch blade into "on" position except when the door is closed.
6. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, a stationary member fixed adjacent said plate having a slot therein, and means connected to move with the door having a part extending into the slot of said plate adapted to prevent movement of the switch blade into "on" position except when the door is closed.
7. A switch mechanism comprising a casting having an opening thereinto, a door for said opening, a switch blade, operating means for operating the switch blade, said operating means including a pivotally mounted plate having a slot formed therein, one portion of said slot being concentric with the pivot of said plate and another portion of said slot extending radially from said pivot, a stationary member fixed adjacent said plate having a slot therein, and means connected to move with the door having a part extending into the slot of said stationary member and into the slot of said plate adapted to prevent opening of the door except when the switch blade is in the "off" position.
8. A switch board comprising a supporting member, a movable switch blade supported thereby, means forming an enclosure for the switch blade including a guard door, operating means for operating the switch blade including a movable plate having a slot therein parts of which extend longitudinally in different angular directions, and means movable along said slot from one part thereof to the other and extending into connection with the door adapted to prevent movement of the switch into "on" position except when the door is closed.
9. A switch board comprising a supporting member, a movable switch blade supported thereby, means forming an enclosure for the switch blade including a guard door, operating means for operating the switch blade including a movable plate having a slot therein parts of which extend longitudinally in different angular directions, and means movable along said slot from one part thereof to the other and extending into connection with the door adapted to prevent opening of the door except when the switch is "off".
10. A switch board comprising a supporting member, a movable switch blade supported thereby, means forming an enclosure for the switch blade including a door, a member connected to move with the door, and operating means for the switch blade including a movable part having a slot

therein into which the member connected with the door extends, said slot having a portion disposed to allow movement of the member connected with the door when the slotted part is in one position and having another part providing a wall disposed to obstruct movement of the member connected with the door when said slotted part is in another position, all whereby to pre-

vent movement of the switch into "on" position except when the door is closed. 10

In testimony whereof I affix my signature in the presence of two witnesses.
